UNITED STATES PATENT OFFICE

JAMES L. NELSON, OF ST. LOUIS, MISSOURI, ASSIGNOR TO C. NELSON MANUFACTURING COMPANY, OF ST. LOUIS, MISSOURI, A CORPORATION OF MISSOURI

METHOD OF MAKING LIQUID CONTAINERS AND CONTAINER SO PRODUCED

Application filed January 10, 1929. Serial No. 331,507.

This invention relates to the method of making a liquid container and an object is to provide an improved method and means for obtaining an impervious joint between a cast member and adjacent portions of a sheet metal tank forming the walls of a liquid container.

Another object of the invention is to provide an improved impervious joint between a casting and the connected edges of the sheet metal wall of a liquid container so that the joint will resist permanently the attacks of the liquids and solutions contained in the tank.

Other objects are to obtain all of the advantages resulting from the improved structure herein disclosed, reference being made to the accompanying drawings wherein

Fig. 1 is a side elevation showing the casting mounted in an opening in a sheet metal wall by my improved method to obtain an impervious joint.

Fig. 2 is an end elevation of the casting, the lower edge thereof being shown united with the sheet metal wall by my improved joint.

Fig. 3 is a cross sectional view on the line 3—3 of Fig. 1.

The invention is shown embodied in a practical construction used in brine tanks in refrigerating apparatus wherein the cast bracket 1 is mounted in the opening formed by the removal of a portion of a sheet metal wall 2. A purpose of the invention is to obtain an impervious joint between the casting 1 and the wall 2. In each vertical edge of the casting 1 a channel or groove 3 is formed and a similar channel or groove 4 is formed along the lower edge of the casting 1. The ends of the grooves 4 open into the lower ends of the grooves 3 so that a continuous groove is formed along the vertical and lower edges of said casting.

After the casting has been appropriately formed with the grooves in the manner stated the walls of said grooves are tinned. The marginal edges of the wall 2 around the opening in which the casting is to be placed are also tinned. Next, the casting is placed in position in the opening in the sheet metal wall. When the casting is in proper position

in said opening the tinned vertical marginal portions of the sheet metal wall at the sides of the opening therein are seated within the vertical grooves 3 and the horizontal tinned marginal portion of the sheet metal wall at the lower end of said opening is seated in the channel or groove 4, a close fit between said parts being provided.

When the casting is fitted in position in the opening in the sheet metal wall the marginal edges of the sheet metal preferably contact with the bottom walls of the channels or grooves 3 and 4 so that there is close contact between the tinned surfaces of the walls of the channels or grooves and the tinned surfaces of the marginal portions of the sheet metal wall around the opening in which the casting is located. And this contact of tinned surfaces exists also between the edges of the opening in the sheet metal wall and the bottoms of the channels or grooves 3 and 4.

It will be seen that when the casting is positioned in the opening in the sheet metal wall in the manner stated the edges of the casting laterally from the channels or grooves 3 and 4 form shoulders 5 along the inner and outer sides of the sheet metal wall. The walls of the shoulders 5 intersect the surfaces of the sheet metal wall and form therewith angular channels or grooves along the vertical side edges and along the lower horizontal edge of the casting. All of these angular grooves are filled with solder 6 which, by union with the wall 1 and with the shoulders 5 throughout the length of said shoulders along the lower and both vertical sides of the casting, forms a tight joint. And, by cooperation with the tinned surfaces of the sheet metal wall and of the casting, this solder forms an impervious joint that will strongly resist deterioration by the brine solution contained in the tank.

By producing this improved joint by the method described I am enabled to dispense with the use of packing and gaskets and also am enabled to dispense with the use of fastening elements such as bolts or the like. Further, I obtain a joint between the casting and the sheet metal wall of the tank that will resist deterioration longer than any packing or gasket with which I am familiar. The

invention may be varied within equivalent limits without departure from the nature and principle thereof.

What I claim and desire to secure by Letters Patent is—

- 6 1. A method of securing a casting in an opening in a sheet metal wall which consists in forming a groove in the edges of the casting, tinning the walls of said groove and the 10 marginal portions of the sheet metal wall around the opening in which the casting is to be mounted, then placing the casting in said opening with the marginal edges of the sheet metal wall around said opening confined 15 closely in said groove, and then applying along the edges of the casting at opposite sides of the sheet metal wall and against the surfaces of said wall continuous and impervious lines of solder.
- 20 2. A tank comprising a sheet metal wall having an opening therein provided with tinned surfaces along the marginal edges of said wall about said opening, a casting having grooves in its edges, the walls of which 25 grooves are tinned and which casting is located in said opening, and the marginal edges of the sheet metal wall about said opening being received in said grooves, and solder uniting the edges of the casting with the 30 faces of the sheet metal wall at the sides of said grooves on both sides of said wall.
